UNITED STATES PATENT OFFICE.

JOHN F. STANDISH, OF WINTHROP, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

BLANK-HOLDER.

1,271,792.

Specification of Letters Patent.

Patented July 9, 1918.

Application filed November 16, 1914. Serial No. 872,461.

To all whom it may concern:

Be it known that I, JOHN F. STANDISH, a citizen of the United States, residing at Winthrop, in the county of Suffolk and 5 State of Massachusetts, have invented certain Improvements in Blank-Holders, of which the following description, in connection with the accompanying drawings, is a specification, like reference characters on the 10 drawings indicating like parts in the several figures.

This invention relates to a blank holder and, more particularly, to a holder for retaining a top lift or heel blank in position 15 to be attached to a shoe in a heelng machine.

The object of the present invention is to provide a heel or top lift holder with mechanism permitting the proper location and holding of blanks of an unsymmetrical contour such, for example, as characterizes a 20 right or a left heel. It will be understood that the breast edge of a right or left heel is oblique to the longitudinal central line of the heel, the inclination for a right heel 25 being opposite to that for a left heel.

An important feature of the invention consists in a heel or top lift holder provided with gages constructed and arranged to engage the edges of a blank; one of the gages 30 being invertible relatively to the remainder of the holder and so formed that by its inversion the holder is adapted to position and retain blanks of a different contour.

The embodiment of the invention herein shown and specifically described comprises a rear gage formed to engage opposite sides 35 of the curved end of a heel or top lift and an oblique breast gage held yieldingly toward the rear gage and arranged to engage 40 the breast edge of the blank at a plurality of points, preferably along its entire length.

In order to be most effective in practice, it is desirable that the construction of the holder be such as to accommodate heels or 45 top lifts of either of the contours which characterize a right and a left heel respectively. In accordance with the present invention, the breast gage is arranged for adjustment to permit a blank of either form 50 to be held properly.

In holders of this class, it is desirable that it shall be possible to make the change in adjustment from right to left, or vice versa, as expeditiously as possible and that

the construction be of the utmost simplicity 55 compatible with the object sought to be attained. I have secured the desired results by constructing a breast gage in the form of a bar having parallel edges, formed to correspond to the contour of the breast edges 60 of a right and a left heel respectively. I mount the bar in a manner to permit it readily to be inverted, and am thus able to change the adjustment of the holder from 65 right to left, or vice versa, practically instantaneously by a single, simple movement. A breast gage embodying the present invention may be constructed to accommodate 70 blanks having breast edges of any desired contour, and I believe that the blank holder 75 of the present invention is the first in the history of the art capable of conforming to both right and left blanks, the breast edges of which are formed as ogee or reverse curves.

The holder shown in the drawings is of 75 the same general type as that illustrated in U. S. Patent No. 884,513, to B. F. Mayo, granted Apr. 14, 1908, but it should be understood that this particular type of holder 80 has been selected only for convenience in illustration; and that the invention is not limited in its application thereto, but is capable of embodiment in blank holders of 85 various forms.

In the drawings:

Figure 1 is a plan view of a heel or top lift holder embodying the present invention showing an unsymmetrical blank held in 90 place;

Fig. 2 is a view, similar to Fig. 1, showing a blank with a breast of reverse obliquity in the holder;

Fig. 3 is a view, similar to Figs. 1 and 2, showing a holder arranged for unsymmetrical blanks having a different contour from 95 those shown in Figs. 1 and 2, and

Fig. 4 is a front elevation, partly in section, showing the construction and mounting of the breast gage.

Referring to the drawings, 10 represents a plate upon which the elements of the blank holder are mounted. A stationary block 12 is secured to the plate 10, and in it are formed guides in which the shanks 14 and 105 16 of the rear and breast gages 18 and 20, respectively, are mounted for sliding movement.

The rear gage 18 is in the form of a fork adapted to engage the curved rear ends of heel or top lift blanks of various sizes and shapes. An ear 22 extending upwardly from the shank 14 is engaged by a screw 24 having a stationary bearing 26 on the plate 10, thus providing for forward and rearward adjustment of the rear fork 18. The shank 16 has an ear 28 near its front end and a tension spring 30 is anchored at one end in the ear, while its other end is anchored in any one of a series of holes 32 in the plate 10, to provide for adjustment of the tension of the spring. The spring 30, as will be seen, tends to draw the breast gage 20 toward the rear gage 18, for the purpose of holding the blank 34 in position between the said gages.

The construction just described is substantially similar to that disclosed in the patent hereinbefore referred to. According to the present invention that part of the breast gage 20 which engages the blank is not normal to the central longitudinal axis 25 of the holder but lies in a general direction oblique thereto. By this arrangement the holder is adapted to retain an unsymmetrical blank, such as a right or left top lift or heel having an oblique breast edge, in correct position for proper attachment to a shoe. The contour of the breast gage will preferably be made to correspond to the shape of the particular blank to be handled, that shown in Figs. 1 and 2 being in the 35 form of an ogee, or reverse curve, as in the case of what are known to the trade as "anatomic" heels. The breast gage shown in Fig. 3 is formed to locate properly a right or left blank having a straight breast edge, or one having a simple concave curvature.

The opposite edges of the breast bar 20 are parallel and the gage is formed with a cylindrical extension 36 which enters a bearing 38 formed in the end of the shank 16. 45 A screw 40, threaded in the end of the cylindrical extension 36, retains the breast gage in its bearing and permits rotation of the gage about the axis of the said extension. The free end of the gage 20 is formed with 50 a tongue which slides in a guide 42 secured to the plate 10. The gage also rests upon the plate 10 and by its sliding engagement therewith, and by the guide 42, rotation about the axis of the cylinder 36 is normally 55 prevented; but when it is desired to change from the right top lift or heel, shown in Fig. 1, to the left top lift or heel, shown in Fig. 2, the breast gage may be drawn forward against the tension of the spring into 60 the dotted line position of Fig. 2, where it is free from the plate 10 and the guide 42 and may be easily and quickly turned about the axis of the cylinder 36 until it is inverted, whereupon the contour of the blank 65 engaging edge of the gage is reversed and

it is adapted to hold a left top lift or heel. Upon being released, the spring 30 draws the gage back into the guide 42 and it is held from rotation as before.

In Fig. 3 the breast gage is shown in 70 solid and dotted lines in the two positions for engagement with left and right blanks and, except for the shape of the breast line, the construction is substantially the same as 75 in Figs. 1 and 2.

It will be observed that by making the gage 20 reversible by inversion its opposite edges may be formed to fit a pair of blanks having breast edges of any form, however complicated. A holder embodying this invention has no loose, separable parts liable to become lost or damaged, and the desired results are secured with the utmost simplicity and ease of manipulation.

Having described my invention, what I 85 claim as new and desire to secure by Letters Patent of the United States is:

1. A heel or top lift holder having a gage for engaging one edge of a heel or top lift, a relatively invertible gage for engaging the 90 other edge of the heel or top lift, and means for effecting relative approaching movement of said gages, to seize a blank between them.

2. A heel or top lift holder having a breast gage invertible relatively to the remainder of the holder, said breast gage being constructed and arranged to conform to the breast edges of blanks having breast edges of different contours by engagement 95 with said edges.

3. In a blank holder of the class described, a plurality of gages arranged to retain a blank in a predetermined position by engagement with the edges of said blank, one of said gages being invertible relatively to the other, about an axis extending transversely of the holder, to an alternative blank engaging position.

4. In a holder for heel or top lift blanks, a pair of horizontally oppositely arranged relatively unsymmetrical gages, one of said gages being reversible relatively to the other about a horizontal axis.

5. In a holder for heel or top lift blanks, a rear gage, and a breast gage having opposite site edges formed to engage the breast edges of right and left blanks, respectively.

6. In a holder for heel or top lift blanks, a rear gage, and a breast gage movable into two positions and constructed to conform to the contours of right and left blanks having curved edges in said two positions, respectively.

7. In a device of the class described, a single blank engaging member having different blank engaging portions conforming respectively to the breast contours of right and left heels or top lifts having curved breast edges.

8. In a device of the class described, a

- single blank engaging member having blank engaging portions conforming to the breast contours of both right and left heels or top lifts having breast edges in the form of 5 ogee curves.
9. In a heel or top lift holder, a rear gage, and a breast gage reversible by inversion and having opposite, parallel, work engaging portions.
10. 10. In a heel or top lift holder, a rear gage and a breast gage having two parallel, curved, work engaging edges.
11. In a heel or top lift holder, a breast gage having a plurality of blank engaging edges movable, respectively, into positions 15 of reverse obliquity relative to the longitudinal central line of the holder.

In testimony whereof I have signed my name to this specification in the presence of two subscribing witnesses.

JOHN F. STANDISH.
